UNITED STATES PATENT OFFICE.

HOWARD W. FITZ, OF CHICAGO, ILLINOIS.

DESIGN FOR A TOILET-STAND.

SPECIFICATION forming part of Design No. 25,731, dated June 30, 1896.

Application filed April 23, 1896. Serial No. 588,830. Term of patent 3¹ years.

To all whom it may concern:

Be it known that I, HOWARD W. FITZ, a citizen of the United States, and a resident of Chicago, in the county of Cook and State of

Illinois, have invented and produced a new and original Design for Toilet or Wash Stands, of which the following is a specification, reference being had to the accompanying drawing, forming a part hereof.

10 This design relates to toilet or wash stands, and has for its object to produce a novel, useful, and ornamental stand which shall present to the eye a distinguishing and characteristic appearance.

15 The leading feature of my design consists of a rectangular casing mounted upon one end and having a flat top with rounded edges and a circular opening at its upper end, from which rises perpendicularly at its rear a framework having narrow side pieces and a paneled face.

20 In this face is inserted at the upper portion a mirror-faced door, and a shelf projects immediately beneath said door, while the outer edges or sides form a neat frame or graceful molding about the casing, substantially as shown.

The design is illustrated in the accompanying drawing, in which the figure represents a perspective view of a toilet-stand embodying the design.

30 In said drawing, A designates the body portion or casing of the stand, this casing of upright rectangular form being paneled on its four sides, and provided with a door and fastenings *a* on its front face. The top *B* is flat, having rounded and overhanging edges with a circular opening *b* in its center, in which is located a bowl *c*. The reservoir-back *C*, rising perpendicularly at the rear, supports and conceals a reservoir. Upon its face are mounted the mirror-faced door *d*, the shelf *e*, hooks *f*, and the faucet *g*, overhanging the bowl *c*.
35 What I claim is—
40

The design for a toilet or wash stand herein shown and described.

HOWARD W. FITZ.
